UNITED STATES PATENT OFFICE

166,848

CIGARETTE HOLDING AND DISPENSING
DEVICE

Blake H. Brown, Roanoke, Va.

Application March 24, 1952, Serial No. 19,032

Term of patent 14 years

(Cl. D85—2)

To all whom it may concern:

Be it known that I, Blake H. Brown, a citizen of the United States, residing at Roanoke, in the county of Roanoke and State of Virginia, have invented a new, original, and ornamental Design for a Cigarette Holding and Dispensing Device, of which the following is a specification, reference being had to the accompanying drawing, forming part thereof.

Figure 1 is an elevational view of a cigarette holding and dispensing device, showing my new design; and

I claim:

The ornamental design for a cigarette holding and dispensing device, as shown.

BLAKE H. BROWN.
